UNITED STATES PATENT OFFICE.

HENRY K. SANDELL, OF CHICAGO, ILLINOIS, ASSIGNOR TO HERBERT S. MILLS, OF CHICAGO, ILLINOIS.

RECTIFIER.

1,208,384.

Specification of Letters Patent. Patented Dec. 12, 1916.

Application filed March 3, 1914. Serial No. 822,135.

To all whom it may concern:

Be it known that I, HENRY K. SANDELL, a citizen of the United States, residing at Chicago, in the county of Cook and State 5 of Illinois, have invented a new and useful Improvement in Rectifiers, of which the following is a specification.

My invention relates to certain new and useful improvements in rectifiers and is 10 fully described and explained in the specification and shown in the accompanying drawings, in which:—

Figure 1 is a longitudinal section through my improved device; Fig. 2 is an end view 15 looking from the left of Fig. 1; Fig. 3 is a section on the line 3 of Fig. 1; Fig. 4 is a section on the line 4 of Fig. 1; Fig. 5 is a section through the stator on the line 5 of Fig. 4, and Fig. 6 is a circuit diagram.

20 Referring to the drawings, 7 generally indicates the stator which is of the type common in induction motors except for the windings hereinafter described. Mounted within the stator is the rotor 8 carried by a 25 shaft 9. The rotor is provided with the usual pole-pieces of radial form, main coils 9^a, starting-coils, and with the slip-rings 10 and 11 through which the current can be led in from the brushes. A centrifugal device 30 for cutting out the starting coils is shown diagrammatically in Fig. 6 and this is, or may be of any desired construction. In the form shown, it consists of a conducting piece 12 having electrical connection with 35 the slip-ring 11 and contacting with a pin 13 electrically connected with the starting coils which are shown at 14. When the rotor is moving at the desired speed, the piece 12 moves away from the pin 13, cutting out 40 the starting coils.

The parts thus far shown and described, 45 it will be seen, are those of the common induction motor in which the current is led to the rotor through slip-rings, and the stator is of an induction type and carries the induced currents. This type of motor is highly advantageous for use in a rectifier of small size because it is self-starting, because it is very cheap and is thoroughly practical 50 for small-sized devices. In using the device, however, for rectifying purposes, it must be got into step and must remain in step and, therefore, in some manner it becomes necessary to eliminate the slip which is the 55 characteristic of induction motors. In other

words, the induction motor must be made to run synchronously. This is accomplished by inserting into the field or stator two coils 15 in series with each other and so wound as to produce localized fields of opposite polarity, which coils 15 are excited by the rectified current produced as hereinafter specified. The result of this construction is that there are provided in the stator, by means of the rectified current, localized poles, and it 60 is found in practice that the rotor will then stay in step and run synchronously. Whether this would be true if the rotor were doing any heavy work has not been determined because there is no necessity for making such determination in a rectifier. The only requisite is that when doing practically no work at all, that is, when merely moving the commutator, hereinafter to be described, the rotor shall run synchronously. Under 65 70 this light load the slip would be very slight in any event and the presence of the two fixed poles is sufficient to maintain synchrony.

The shaft at the left of the rotor is hollowed out to receive conductors 16 which 75 carry the unrectified current. These conductors, it will be noted, are in parallel with the coils of the rotor. The shaft 9 has fixed upon it a disk 17 carrying two circular sets 80 of segments, 18, 19, 20 and 21, arranged in two circles, and the evenly-numbered segments 85 of the two sets being in electrical connection with each other and connected to one of the conductors 16, while the odd-numbered segments are likewise in electrical connection 90 with each other and connected to the other conductor 16. In other words, the segments 18 and 20 take current from one conductor, and 19 and 21 from the other conductor. Bearing upon these segments are brushes 95 22 and 23 which lead off the rectified current and from which the connections run to the coils 15, heretofore referred to as placed in the stator for the purpose of maintaining synchrony.

100 It is believed that the operation of the device will be readily apparent from the description of its construction. The alternating-current is led in through the brushes on the slip-rings 10 and 11, energizing the main 105 and starting coils of the rotor. When the rotor is up to speed, which is nearly a synchronous speed, the slip being naturally very small, the current led out of the brushes bearing on the commutator segments will al- 110

ternate only very slowly. It will obviously alternate only as often as the slip amounts to a quarter turn of the rotor. During any one of the periods of flow of the current thus issuing from the commutator brushes, the coils 15 in the stator can become energized and establish localized poles in the stator, so that thereafter the rotor will run synchronously and the direct current can be 10 continuously drawn from the commutator brushes and utilized in any desired manner as, for instance, in the motor which is shown diagrammatically in Fig. 6 as having connection therewith. Of course, as soon as the 15 rotor is moving at a sufficiently high speed, its starting coils are cut out in the usual manner.

The mechanical structure here shown is very simple and is peculiarly designed for 20 rectifying currents of relatively-small volume. The motor is, or may be, of a type commonly sold on the market at a very low price, varied only by the introduction of the coils into its stator. It requires no modification except the addition of these coils and the provision of the commutator at one end. By permitting current to flow direct from the slip-rings to the commutator-segments instead of through the armature, a considerably greater volume of current can be rectified than could be safely passed through the armature. In the motor selected the 25 rotor is the part affected by the alternating current because, by such construction, the 30

necessary number of movable parts is reduced to the minimum.

I realize that considerable variation is possible in the details of the construction herein shown, and I do not intend to limit myself thereto, except as pointed out in the 40 following claim, in which it is my intention to claim all the novelty inherent in the device as broadly as is permitted by the state of the art.

I claim as new and desire to secure by 45 Letters Patent:

A device of the character described comprising a motor of the induction type having a primary rotor and a secondary stator, a commutator, one member of which is 50 driven by the rotor, slip rings carried by the rotor from the slip rings to the rotor windings and from the slip rings to the driven commutator member, two windings in the 55 secondary member, one of which is short circuited and the other of which consists of coils, leads for drawing off rectified current from the stationary member of the commutator and for leading the rectified current therefrom to the coil winding of the stator.

In testimony whereof I have hereunto set my hand this 23rd day of February, 1914.

HENRY K. SANDELL.
